UNITED STATES PATENT OFFICE.

GEORGE WESTINGHOUSE, JR., OF PITTSBURG, PENNSYLVANIA.

SWITCH AND SIGNAL APPARATUS.

SPECIFICATION forming part of Letters Patent No. 240,629, dated April 26, 1881.

Application filed January 8, 1881. (No model.)

To all whom it may concern:

Be it known that I, GEORGE WESTINGHOUSE, Jr., of Pittsburg, county of Allegheny, State of Pennsylvania, have invented or discovered a new and useful Improvement in Switch and Signal Apparatus; and I do hereby declare the following to be a full, clear, concise, and exact description thereof, reference being had to the accompanying drawings, making a part of this specification, in which—like letters indicating like parts—

Figure 1, Sheet 1, is a ground plan or diagram of a system or arrangement of switches, switch-actuating mechanism, signal-posts, and signal and switch-pipe connections for actuating the switches and signals from a single point, or from a switchman's cabin. Fig. 2, Sheet 2, is a diagram view, to a somewhat larger scale, of the apparatus employed in the switchman's cabin, by the use of which to apply the operative fluid-pressure in any desired order for the proper actuating of switches and signals. While these two views show with sufficient fullness many of the features of construction, and some of the operative combinations hereinafter claimed, they are also intended to illustrate the manner of applying, generally, my present invention in a system of fluid-pressure switches and signals, from which, and 30 the explanation hereinafter given, the skilled constructor will understand how to apply and use the invention in the organization of similar mechanism for the actuating of other arrangements of switches and signals. Fig. 3, Sheet 1, shows in elevation, to an enlarged scale, a signal-post, signals, and operative mechanism suitable for use at each of the signal-points marked S' S² of Fig. 1. Fig. 4, Sheet 1, is a longitudinal sectional view, to an enlarged scale, of a differential cylinder and piston device, such as I prefer to use for the purpose of transmitting the operative fluid-pressure to the movable switch-rails. Fig. 5, Sheet 2, is an enlarged top view of one of the diaphragm-boxes of Fig. 2. Fig. 6 is a vertical sectional view of the diaphragm-box of Fig. 5. Fig. 7, Sheet 3, is a view in elevation (slightly enlarged) of the series of valves shown in the front of Fig. 2, and of the interlocking apparatus used in connection therewith. Fig. 8 is a rear-end view, to an enlarged scale, of one of

the valves of Fig. 7. Fig. 9 is a longitudinal sectional view of one of such valves in the plane of the line x x of Fig. 8, and also through the interlocking devices (enlarged) in the plane 55 of the same line of Fig. 7. Fig. 10 is a sectional view in the plane of the line x' x' of Fig. 9, looking to the left. Fig. 11 is a sectional view, showing the valve-ports in the plane of the line y y, Fig. 8. Fig. 12 is a detached view, 60 in perspective, of the valve proper, showing its seating or bottom face. Figs. 13 and 14 are detached views of the front and rear sector-plates employed in operating the locking apparatus. Fig. 15 is a top or plan view of the 65 devices of Fig. 7; and Figs. 16 and 17 are detached side views of the locking slide-bars employed as presently to be explained; and Fig. 18 is an enlarged view, in perspective, of the joints of the rotating sleeves of Fig. 7, as presently to be explained. 70

My present invention relates to certain features of improvement in what is commonly known as "fluid-pressure switch and signal apparatus," and more particularly to that class of such apparatus in which the shifting of the signals and switches is in each case to be effected by putting in motion a close hydraulic column, which is interposed between the switch or signal actuating devices and one side of a flexible 80 diaphragm, and in which, also, such close hydraulic column is put in motion by applying compressed air to, and releasing it from, the other side of such flexible diaphragm. And my invention also includes the arranging of a 85 series of two or more such diaphragms on one or more of such close hydraulic columns, with a compressed-air pipe-connection to each, whereby such hydraulic column may be employed for moving a signal or a switch, in combination with any desired one of two or more other hydraulic columns. And I include also, as a part of my present invention, an improved valve-motion, whereby the compressed air may be turned on to any predetermined number of 90 diaphragms, so as to secure the shifting or moving of the desired signals and switches, and at the same time, by further improvements, effect the locking of all other valves, so that the signals and switches which ought not at 95 that time to be moved cannot be. And I also include other features of construction and op- 100

eration, the details of which are substantially as hereinafter set forth and claimed.

Referring to the diagram, A' may represent a switchman's cabin, in which all connections are to be centered, and in which is to be arranged the valves, valve-levers, and interlocking-bars, in convenient position for operation.

A may represent the right-hand track of a double-track road, (looking to the left, which may be assumed to be in an easterly direction,) and B the left-hand track.

C, D, F, and G represent switches and sidings diverging from the main tracks; and at E, I have shown a cross-over, and another at H. In convenient proximity to each switch, and properly arranged for moving the switch by a piston-stroke, is a switch-cylinder provided with a piston, and these cylinders, arranged at or opposite their respective switches, I have numbered 1 to 8.

Signal-posts and signals of suitable construction (such, for example, as are shown in Fig. 3) are put up at proper points, and in the present system I have represented eight such points, which I have lettered S' to S⁸. Each signal-post has thereon, or in convenient proximity thereto, a signal-cylinder, s, Fig. 3, having a piston therein, the stem s' of which has a suitable connection with a semaphore, s², or other known form of day or night signal, such as will impart to it the desired motion. And while the construction, form, or style of signal may be varied at pleasure, the one shown will answer the present purpose. I have shown in the same figure a signal-lantern, s³, and a colored lens, s⁴, for night signaling. The ordinary operation of these or other similar devices is assumed.

From one end (preferably the back end) of each switch-cylinder I carry a hydraulic pipe to a convenient point at or near the cabin. These pipes I have lettered a' to a⁸. A like series of hydraulic pipes, c' to c⁸, extend from the several signal posts or points to a like convenient point in or near the cabin. Each pipe, whether signal or switch, terminates in or has connected therewith, preferably at or near its cabin end, one or more diaphragm-boxes, e' to e⁸, Fig. 2, the construction of each diaphragm-box being substantially as represented in Figs. 5 and 6, where e represents the diaphragm-box proper, and e²⁴ a flexible diaphragm therein. The connection of each hydraulic pipe with its diaphragm-box, or with each diaphragm thereon, is by a port, e²⁵, beneath the diaphragm. A like port, e²⁶, leading from the open space of the box above the diaphragm, makes connection by a pipe with a valve-box, of which several are shown, which are lettered P' to P⁸; but for convenience of illustration and lettering I have, in Figs. 8 to 10, indicated it by the letter P, P¹⁰ being the cap. The pipes connecting the diaphragms and valve-boxes are marked z' to z²³.

It will now be readily understood that if, by the use of suitable valves in the boxes P' to P⁸,

air-pressure be turned on or applied through the pipes z' to z²³, or through any of them, the pressure so transmitted, acting on the tops of the corresponding diaphragms in the dia-phragm-boxes e' to e²³, will force the water or other liquid out of the chambers beneath such diaphragms through the corresponding pipes leading thence to the signal or switch-actuating mechanisms, and by actuating the latter shift the switches over to make the desired track-connections, and also will shift the appropriate signals to safety positions. The amount of liquid, preferably non-freezing, in each hydraulic column is, as near as may be, sufficient to 80 fill its diaphragm box and pipe, and the actuating-cylinder at the switch or signal, up to the point at which the piston or diaphragm should begin its proper movement, and hence I term it a "close column." On the release of the fluid-pressure from the pipes z' to z²³, or such of them as may have been charged, the pressure on top of the several diaphragms will be released, and on the back-flow of the hydraulic columns, shifting the diaphragms and filling the chambers beneath, the switches will receive a reverse throw, and the signals will come to "danger;" and for the purpose of causing such back-flow, if need be, and reversing the switches and signals, a spring or weight may be employed, or a back-acting fluid-pressure, as presently to be explained.

While, in connection with the system of constructing and operating signals and switches herein described, I do not limit myself to any particular form of valve for turning on or applying and turning off or exhausting the air-pressure, I have shown in Figs. 8 to 14 a suitable construction of valve for the purpose.

P represents the valve-box, closed by a cap, P¹⁰, and wherein is a rotary valve, v, made of a disk form, with two projecting lugs, v', on its back face, by which, through counter-lugs w' on rotary wrench w, to give it the proper motions. The valve has a port, v², preferably oblong in form, extending through it, so that compressed air, admitted by the port p to the space between the valve v and its operating-wrench w, may be admitted through the port v² to a port, v³, which communicates with the pipe or pipes leading to the switch-operating diaphragms e⁵ to e¹⁹, and also to a port, v⁴, which communicates with the pipe or pipes leading to the signal-operating diaphragms e' to e⁴ and e²⁰ to e²³.

As it is desirable that the switches be moved or shifted preparatory to the movement of a train, in advance of the movement of the signals which indicate "safety" or "line clear" on the line of track so made, it is important that the air be turned onto the pipe-communications in the order above set forth—that is to say, so that, first operating through v³, it shall put the proper hydraulic column or columns in motion for shifting the switches—and this is done by causing the forward end (in the direction of its motion) of the port v² to register first with the

port v^3 —and next, by a further movement of the valve, so that the port v^2 shall register with v^4 , the communications shall be such that the air-pressure so passing through v^4 shall put the proper hydraulic column or columns in motion for properly shifting the signal or signals for the track-line previously made; and this is the reason for preferring the oblong form of port. The valve v also has a cavity or chamber, v^5 , on its under or seating face, of such form that, on a reverse movement of the valve, (which first cuts off the supply,) such cavity acts as a connecting-port between the ports v^3 v^4 and an exhaust-port, v^6 , leading to the open air; hence when the cavity v^5 comes over the ports v^3 and v^4 the previously-applied air-pressure will escape through the port v^6 , and the previously-moved hydraulic columns will make a return-stroke or flow back to fill their respective dia-phragm-boxes, under the action of any suitable reverse force applied to the pistons at the switch and signal ends of such columns, and for this latter purpose a spring, weight, or back-acting fluid-pressure may be employed; hence the previously-moved switches and signals will thereby be reversed in position. And it should also be observed that the reverse movement of the valve v , as described, will first uncover the port v^4 , which is the signal-actuating port, as a result of which the corresponding signals will come to a "danger" position in advance of the reverse shifting of the switches, which is an important feature in apparatus of this class.

It should also be noted that when the pressure is turned on the flat face of the valve covers the exhaust-port v^6 . The valve and its actuating-wrench are kept apart, and the valve is held to its seat in the bottom of the valve-box by a coiled-wire spring, w^1 , and the necessary packing is added, as at w^2 , for making a tight joint. The wrench-stem w^4 projects through the cap P^{10} , and on its projecting end is keyed or otherwise secured a sleeve, g' , on which is made or secured an operating valve-handle, g .

For convenience in construction, what I herein speak of as a "sleeve," g' , may be made in sections, as indicated in Fig. 9; but in such case all the sections are to be keyed or otherwise secured to the stem w^4 , so that all shall move or rotate together; hence all the sections will constitute, mechanically, a single sleeve, and as such I designate them all by one letter, g' .

On valve-boxes P' and P^2 , Fig. 7, the handles are prolonged, so as to form crank-arms g^2 , and on each of the sleeves of the other boxes, P^3 to P^8 , are two sector-plates, h h' , the arrangement of which on the stems relative to each other is as represented in Figs. 7 and 9, and the function of which will presently be explained; but it should also be stated that the valve-boxes P' and P^2 contain valves only for actuating signals, and hence in these the ports v^4 , for switch-pipe connections, may be omitted or closed.

In further description I will, for convenience, simply speak of the devices at P' to P^8 , Figs. 2,

7, and 15, as valves. Such valves may, for convenience in locking and unlocking, be arranged in a row, side by side, and in compact order, as in Fig. 7, and the handles g may in the successive valves of the series be arranged at different distances from the ends of the stems, so that as the valves are rotated the handle of one valve may pass that of the next; or the valves may be arranged farther apart than is indicated, so that the handles arranged in the same vertical plane shall not strike or engage each other; but the front sector-plates, h , of all the valves should be in line with each other, or in a common vertical plane, and likewise the rear sector-plates, h' . Extending along between the two series of sector-plates thus formed is a cylindrical bar, D' , Fig. 9, on which are a series of sleeves, d d' d^2 , Figs. 7 and 15, the number and length of each of which may be varied, in accordance with the work to be done, on principles presently to be explained. Each sleeve turns readily on the bar D' , and locking-arms n n' project out radially from the sleeves, one pair—that is, a front and rear one—beneath each pair of sector-plates h h' . Under one—say the rear—series of these locking-arms are two notched bars, B' B^2 , of which the one, B' , is connected with the crank-arm g^2 of the valve P' , and the other with the crank-arm g^2 of the valve P^2 .

In the normal position of the apparatus, which is that shown in Fig. 7, the levers of P' and P^2 are turned to the right, so as to turn on the fluid-pressure from P' through z' to diaphram e' on the signal-line c' , and thereby set signal at S' to "safety," this being the signal for indicating main line A clear. Also fluid-pressure is turned on from P^2 , through pipe z^{21} , to diaphram e^{21} on signal-line c^6 , so as to raise signal at S^6 to "safety," this being the signal for the other main track. All other levers are turned to the left, in which position fluid-pressure is turned from the other lines, so that all switches are closed or set to make the main track clear and all the other or the siding-signals are at "danger."

Each front sector-plate has at one end (which I call the forward end) of its periphery a recess, x , Figs. 9, 13, formed by projecting lugs, and at the other or back end a stop-shoulder, x' . Each rear sector-plate has at the forward end of its periphery a lug, x^2 ; and at a little distance therefrom, less, however, than the length of the valve-motion necessary to open the ports v^2 v^3 , it has an incline, x^3 , which terminates in the curved edge x^4 .

The front locking-arms, n , are weighted or pressed or forced down by a spring, so that the tendency will always be to turn the rear arm, n' , upward. With the levers g of valves P^3 to P^8 in the position shown, or turned to the left, Fig. 7, the rear arms, n' , will be turned up into the recesses formed in the rear sectors, h' , between the lugs x^2 and inclines x^3 , and while the arms n' are in this position the valve-levers g will be locked, because they cannot

be moved far enough to open ports v^2 v^3 , except by causing the inclines x^3 to depress the arms n' ; and the arms n' are held in position as against a downward motion by means of the 5 projections b to b^3 on the bar B' , Fig. 16, and the projections b^4 to b^8 , Fig. 17, or some of them, as shown. For reasons which will presently appear, I prefer, in the apparatus as here organized, to arrange the arms n n' of the valve P^3 10 on one sleeve, d , the arms n n' of the valves P^4 to P^6 on another sleeve, d' , and those of the other two valves, P^7 P^8 , on a third sleeve, d^2 . Also, I cut a notch, o , Figs. 7 and 18, on the end of each sleeve d and d^2 , at the end next the intermediate sleeve d' , the length of the notch being 15 equal, or about equal, to the rotary motion of either sleeve in the movement of its arms n n' . In each end of the sleeve d' I insert a pin, o' , so that it shall project into the adjacent notch o , at or near the end of the notch, toward which it will move as d' is rotated. It will now be seen that d or d^2 may be each or both rotated without rotating d' , but that any rotary motion imparted to the latter will cause a corresponding rotation of both the former.

25 As already stated, shifting the handle g of valve P' to the left lets off the pressure, so as to shift the signal at S' to "danger." The same movement also shifts the bar B' to the right, so 30 that the recesses b^{10} to b^{13} shall come beneath the locking-arms n' , which before were held or locked up by the projections b to b^3 . The locking-arms of valves P^3 to P^8 are all then unlocked, so far as the bar B' acted as a locking device; 35 but by reference to Fig. 17 it will be seen that all are still locked by the bar B^2 except P^3 . By moving the lever of this valve over to the right I turn on air-pressure, through pipe z^{18} , to diaphragm-box e^{18} and put in motion the hydraulic column in pipe a^8 , which leads to switch-cylinder 40 8, so as to shift that switch to make a siding connection from main track A to siding F; also, this motion of the valve next turns on air-pressure, through pipe z^4 , to diaphragm-box 45 e^4 on the signal-line c^4 , which leads to the signal at S^4 for siding F, and shifts it from "danger" to "safety." The train may then proceed onto or off of siding F from or to main track A, after which the lever of valve P^3 may be 50 reversed, the signal at S^4 brought back to "danger," and the main-track connection restored. Reversing P' will relock P^3 and put the main-line signal at S' to "safety."

To illustrate how my system of construction 55 and operation may be employed in moving trains from one main track over to a siding outside the other main track or from a siding outside of one main track over to the other main track or to a siding of the same, I will 60 describe a number of operations which may be performed with the apparatus as here represented, and first I will assume that a train is to pass from the main track A, by cross-over H, onto main track B, and then onto siding G, or in the reverse direction: First, the main-track signals should be put at "danger," as a

protection against approaching trains, which is done by shifting valves P' and P^2 to the left, as already described. Thus the bar B' is shifted to the right, as and with the result already stated. Shifting bar B^2 to the right results in bringing the recesses b^{14} to b^{18} under the locking-arms n' of valves P^4 to P^8 , so that the levers of all the valves P^3 to P^8 are then unlocked. Valves P^4 to P^6 being thus unlocked the operator turns valve P^4 . The first effect results from the action of its rear sector-plate, h' , on its locking-arm n' . The incline x^3 depresses the locking-arm, and that causes the partial rotation of the sleeve-section d' , as a result of which the front locking-arms, n , of valves P^5 to P^6 are rotated up into the recesses x of their front sector-plates, h , so as thereby to lock valves P^5 and P^6 . Also, the rotation of d' , thus effected, causes, through the action of the pins o' , the rotation in the same direction of the end sleeves, d and d^2 , as a result of which the front arms, n , of these sections will be rotated up into the recesses x of the front sector-plates, h , of the corresponding valves P^3 P^7 to P^8 , so as also to lock them. Also, the downward movement of the rear locking-arms, n' , thus caused, brings such arms into the recesses b^{10} to b^{13} of bar B' , and b^{14} to b^{18} of bar B^2 , so that these bars are locked, and through them the signal-valves P' P^2 are securely locked, so that while the train is moving over the track from A to G or the other way, or while the track is in condition for such train movement, the main-line signals are locked 95 at "danger." It will also be seen that every valve is locked except the one that is in motion, P^4 . The movement of this valve also lets on pressure, through pipes z^{16} z^8 z^5 , to diaphragm-box e^{16} on hydraulic column a^7 , leading to switch-cylinder 7, also to diaphragm-box e^8 on hydraulic column a^3 , leading to switch-cylinder 3, and to diaphragm-box e^5 on hydraulic column a^1 , leading to switch-cylinder 1. The actuation of the pistons in these cylinders 100 7, 3, and 1 will, as will be seen from the diagram, Fig. 1, make the required track-connection. As soon as this is done air-pressure turned on through signal-pipe z^2 to diaphragm-box e^2 on hydraulic signal-column c^2 will shift 105 signal at S^2 to "safety," and the train may proceed. The reversal of all the operations described in the reverse order restores the entire apparatus to its normal position.

As a second operation, pass a train from siding C onto main track B, thence by cross-over E onto main track A, and thence onto siding F. The operation last described is to be repeated, except that instead of moving valve P^4 the switchman moves valve P^5 . In the manner 110 already described this motion locks all other valves in the manner set forth, and turns on pressure by pipes z^{19} z^{14} z^{12} z^6 to diaphragm-box e^{19} on switch-column a^8 , so as to shift switch-cylinder 8 also to box e^{14} on column a^6 leading 115 to switch-cylinder 6, also to box e^{12} on column a^5 leading to switch-cylinder 5, and to box e^6 120

125

130

on column a^2 leading to switch-cylinder 2, so as to shift the corresponding switches. Like pressure is, by a continuation of the same valve motion, turned on through signal-pipe z^3 to diaphragm box e^3 on hydraulic column c^3 leading to signal at S^3 , so as to shift it to "safety." After the train has passed the apparatus is reversed to normal position, as before.

As a third operation, I will assume that a train is to be run from siding F by main track A, cross-over E, main track B, onto siding D. For this purpose the valves are to be shifted, as before, in the first operation, except that P^6 is moved instead of P^4 . This motion locks P^4 and P^5 by the movement of the locking-arms n n' , and also of all the other valves, in the manner stated. Fluid-pressure is also turned on through pipes $z^{17} z^{18} z^{11} z^{10}$ to diaphragm-box e^{17} on hydraulic switch-column a^8 , also to diaphragm box e^{13} on hydraulic switch-column a^6 , also to box e^{11} on hydraulic column a^5 , and to box e^{10} on hydraulic column a^4 , whereby said hydraulic columns are put in motion so as to operate switch-cylinders 8, 6, 5, and 4 and the corresponding switches. Next, fluid-pressure passes by pipe z^{20} to diaphragm box e^{20} on hydraulic signal-column c^5 to signal at S^5 , so as to clear the appropriate signal for this line. After the train has passed the reversal of the operation again brings all to the normal position.

As a fourth operation, a train may be run from main track B to siding D. For this purpose it is only necessary to shift signal No. 6 to "danger," and this may be done by moving valve P^2 and its bar B^2 so as to bring the recesses b^{17} and b^{18} under the corresponding locking-arms n' of the valves P^7 and P^8 , thereby unlocking these valves. It will be seen from Fig. 16 that these valves are not locked by the bar B' when in its normal position, (which it still retains,) but that all the other valves, P^3 to P^6 , are locked by said bar B' . The switchman now shifts the valve P^7 , and in doing so rotates the sleeve-section d^2 , so as to lock valve P^8 by turning up its front locking-arm, n , into the recess x of its front sector-plate, h , and also locks the bar B^2 by turning the rear locking-arms, n' , of valves P^7 and P^8 into the recesses b^{17} and b^{18} of bar B^2 . Hence all the other valves are locked except P^2 , and as this is the valve for working the main-line signal of main track A, no harm will result from moving it, if the switchman by mistake does so, except to stop all travel on that track. The apparatus being in this condition the switchman, by the shifting of valve P^7 , also turns on pressure by pipe z^9 to diaphragm-box e^9 on hydraulic switch-column a^4 , and through it and its switch-cylinder 4 shifts the corresponding switch. The further movement of the valve P^7 applies pressure through pipe z^{22} to diaphragm-box e^{22} on hydraulic signal-column c^7 , and through it to signal at S^7 , so as to clear the signal for the track thus made, and after the train passes the main track is restored by reversal, as before.

As a fifth operation, a train is to be run from siding G, by main track B, onto siding D. For this purpose the apparatus is worked as in the case last supposed, except that the valve P^8 is to be rotated instead of P^7 . This valve P^7 will be locked by the rotation of d^2 , and the other valves will be locked as before. Fluid-pressure will also be applied, through pipes $z^{15} z^7$, to diaphragm-box e^{15} on hydraulic switch-column a^7 , and to box e^7 on hydraulic switch-column a^4 , so as to operate switch-cylinders 7 and 4 and the corresponding switches. Also fluid-pressure, through pipe z^{23} , will be applied by diaphragm e^{23} on hydraulic signal-column c^8 , so as to shift signal at S^8 to "safety," which is the signal for the line of track so made. Reversal results, as before, in restoration of main track.

While any suitable form of switch-cylinder with piston or diaphragm, double-acting or single-acting, may be employed, I prefer to use at each switch a differential piston and cylinder of the construction substantially as indicated in Fig. 4, Sheet 1. If this construction of switch-cylinder is used, the hydraulic operating-column should be connected with the larger or back end, m , of the cylinder, so as to be operative on the piston of the larger area with sufficient force to throw the movable rails of the switch to make the siding or cross-over connection, and also as against a less effective pressure operative from the other end, m' , of the cylinder on a piston of less area. Preferably the latter pressure is continuously-acting, so that on the release of pressure at the larger end it will always be operative in restoring the main-track connection by giving at once the desired reverse throw. If any pressure leaks past either piston it may be allowed to escape by a small leakage-port, o^2 , made between the pistons. As a suitable means of getting the continuously-acting pressure on the smaller or on the reversing piston, a pipe, u , Fig. 1, of comparatively large diameter may be laid along near the line of switch-cylinders, with a branch, u' , to the reversing end of each. This pipe may be kept charged, like a reservoir, with compressed air to any desired degree of density sufficient for the purpose; and as a motive power for putting the hydraulic columns in motion I may use compressed air from the same pipe, taking it by a branch, u^2 , to the cabin, and thence along over the line of valves to the several ports p , as indicated by dotted lines in Figs. 2 and 15, and by full lines in Figs. 7 to 10. But the source from which the air-pressure is taken is not important as regards the movements described, though, as illustrated, the supply by an air-main is believed to be the best; but hydraulic power may also be applied for giving a reverse motion to the differential pistons, and such pressure may be taken from any suitable or convenient accumulator or other head or supply under pressure; also, the continuously-acting pressure may be applied between the differential pis-

tons, in which case the force acting to give a back-stroke to the pistons will be due to the difference in the areas of the two end pistons. The pressure to give a forward stroke will be applied at the larger end, as before; but I do not limit myself in this part of my invention to any particular arrangement of the ports for introducing the pressures, provided, only, that one pressure shall be continuously acting in one direction, to give a throw or motion in one direction, and a pressure greater in effective power shall at pleasure be operative to shift or impart motion in the other direction, and such greater effect may also be due to a greater degree of pressure, in which case a single ordinary piston may be used; or it may be due to difference in piston-areas, in which case the opposing pressures may be the same in degree; but, as already stated, instead of a fluid-pressure to give a reverse throw, a spring or counter-weight may be employed.

In further explanation of the drawings, it should be stated that the diaphragm-boxes of Fig. 2 will ordinarily be arranged in the cellar 25 of the cabin, and the pipes z' to z^3 will then lead down from a floor above, and I have shown them in diagram form simply for clearness of illustration.

From the description thus given the skilled 30 artificer will understand how to modify forms and proportions, as well as the number of the parts described, with reference to adapting this system of construction and operation to actuating switches and signals in other combinations or ground plans. One valve should ordinarily be provided for each line of track-connection to be made, and a pipe should lead from the port v^3 of such valve to a diaphragm-box on each hydraulic column to be operated 35 so as to shift the proper switches on the motion of that valve; but it will be also possible, and perhaps in some cases advantageous, where two or more switches may enter into either one of two track-combinations, to divide up the 40 combinations, putting the switches common to both combinations into an operative relationship or connection with one valve, and the rest of each of the two supposed combinations into a like relationship with two other valves, so 45 that two valve-motions will be required to make either track-combination. The skilled constructor will also vary the arrangements of notches and recesses on the bars B' B^2 , and the lengths and orderly operation of the sleeves 50 d to d^2 , or other like sleeves on the shaft D' , according to the work to be done. The making 55 up and working out of track-combinations, and of varying the operative machinery with reference thereto, is already a branch of the art, 60 the principles of which are understood by those skilled therein; and unnecessary parts being omitted and the proper modifications made, such as will be within the knowledge of the skilled mechanic, the apparatus may be applied to the switches of a single-track road.

The same features of improvement, some or

all of them, may, by the skilled constructor, be adapted to the moving of railway-gates, as well as of signals and switches, and such use is included herein, it being understood, however, that in the combinations hereinafter claimed a gate-moving mechanism may take the place of a switch-moving mechanism, or be added to the switch-moving mechanism, and that a signal may be provided therefor, either 70 specially or in connection with that switch-moving track combination of which the gate-actuating mechanism may form a part.

In so far as relates to the application of air-pressure at the pleasure of the operator for the 80 purpose of putting a hydraulic column in motion, I do not limit myself to the particular form or construction of valve described, since other valves of like function and operation may be substituted for that described without 85 any substantial departure from the scope of this part of my invention, or even two separate valves may be used, (though less advantageously,) one to apply the pressure and the other to release it.

It should also be stated that two or more of the signals described or referred to may be put on the same signal-post, as already practiced in the art. And my improved system also contemplates the use of carbureted air for 90 night-signals, though no claim is made thereto herein, the same forming a part of the subject-matter of a separate application; but for illustration I have shown in Fig. 3 an air-supply pipe, w^3 , which may be connected with the 95 air-main u , and which leads, through a pressure-regulator, i , and carbureter i' , to the lantern-light. Also, while I believe the interlocking features to be of great importance in 100 apparatus of this character, such interlocking 105 devices may be omitted, if so preferred.

The inclines x^3 of the sector-plates h' , as a means for actuating a movable locking device, operate simply as eccentrics, and any known suitable form of eccentric may take the place 110 of the incline in each case, as the mechanical equivalent thereof, or as substantially the same thing.

If it be desired to operate two or more signals simultaneously in any of the operations 115 such as described, provision may be made therefor by arranging a corresponding number of diaphragm-boxes on the proper hydraulic column, and carrying an air-pressure pipe from the proper signal-valve to each of 120 such diaphragm-boxes, in like manner as is done in the switch-actuating mechanisms.

In a separate application I have described and claimed an organization of block-signaling apparatus having a close hydraulic column actuated by air-pressure, the air-valve being operated by or from the train itself; but the invention therein described is properly an improvement on that herein claimed, to the extent that it takes a part of the present invention and incorporates it in and as a part of 130 a special system of apparatus.

For clearness of description, and in order that my improved system of apparatus may, both in its essential details and as a complete system, be the more readily understood, I have described at some length the interlocking features; but so much of the present apparatus as relates distinctively to interlocking is not included as a part of the invention herein claimed, but the same will form the subject-matter of an application yet to be filed, and will be included in a separate patent. And, in fact, while I believe the interlocking features to be of great importance in apparatus of this character, such interlocking features may be wholly omitted, if so preferred. The remainder of the apparatus will give equally good results, if properly worked, but an element of safety will be lacking; or other interlocking apparatus may be employed with the features of improvement herein claimed.

I claim herein as my invention—

1. The method of operating railway switches, signals, and gates, which consists in causing compressed air to be applied and released to and from the one side of a flexible diaphragm, so as to put in motion a close hydraulic column which extends from the other side of said diaphragm to the signal, switch, or gate actuating mechanism, substantially as set forth.
2. In a switch, signal, or gate operating mechanism, the combination of a close hydraulic column, a compressed-air conduit, an interposed flexible diaphragm, and an operating-valve, substantially as set forth.
3. In combination with a close hydraulic column terminating at one end in signal, switch, or gate actuating mechanisms, a series of two or more diaphragm-boxes arranged on and in communication with such hydraulic column, and a like series of two or more compressed-air conduit-pipes extending to a like series of independent valves, whereby such hydraulic column may be put in motion from any desired one of such valves, substantially as set forth.
4. A system of switch, signal, or gate actuating mechanism having, in combination, a series of close hydraulic columns, each terminating in one actuating mechanism, a series of diaphragm-boxes on such hydraulic columns in excess of the number of columns, a compressed-air conduit connecting each diaphragm - box with a valve device substantially as described, whereby the hydraulic column or columns having more than one diaphragm may be used in combination with other hydraulic columns.
5. The combination of a close hydraulic column terminating in a switch or gate actuating mechanism, a like column terminating in a signal-actuating mechanism, a diaphragm-box on each column, compressed-air conduits leading from such diaphragm-boxes to a valve-case common to both, and a valve having a system of arrangement of ports, substantially as set forth, whereby the air-pressure shall be turned onto the switch or gate column in advance of

the application of air-pressure to the signal-actuating column.

6. A series of close hydraulic columns terminating in a series of switch-actuating mechanisms, and having each a diaphragm - box thereon, and a series of compressed-air conduit-pipes extending one from each of such diaphragm-boxes to a valve common to all, whereby with one motion of the valve all the hydraulic columns of the series may be simultaneously put in motion to make or break a predetermined line of track-connection over a series of successive switches, substantially as set forth.

7. A series of close hydraulic columns terminating in a series of switch-actuating mechanisms, and having each a diaphragm - box thereon, and a series of compressed-air conduit-pipes extending one from each of such diaphragm-boxes to a valve common to all, in combination, by said valve, with a compressed-air conduit leading to the diaphragm-box of a signal-operating hydraulic column, whereby, immediately on the making of the desired line of track-connection over the various switches, by simultaneously moving all, the appropriate signal for such line of track-connection will be shifted on the further movement of the valve, substantially as set forth.

8. In a system of switch and signal actuating apparatus, in which close hydraulic columns are put in motion by air-pressure, so as to shift the switches and signals, a series of valves for applying and releasing air-pressure, of which two, P' P^2 , shall have port and pipe connections for operative main-line signals, and locking devices attached for locking all other valves when main-line signals are brought to "safety," and for unlocking such other valves when main-line signals are brought to "danger," substantially as set forth.

9. In a system of switch and signal actuating apparatus, in which close hydraulic columns are put in motion by air-pressure, so as to shift the signals and switches, and, in combination with such hydraulic columns and with the air-conduits, one or more main-line signal-valves having port and pipe connections for actuating main-line signals, and a series of switch and signal operating-valves in any desired number, having each one or more port and pipe connections for operating the switch hydraulic columns, and also having each at least one port and pipe connection for actuating a signal hydraulic column, substantially as set forth.

10. In combination with a switch-actuating hydraulic column and a signal-actuating hydraulic column, the valve v , having an oblong port, v^2 , by which to turn on an air-supply successively, first through a port, v^3 , leading to the switch-actuating hydraulic column, and next through a port, v^4 , leading to the signal-actuating hydraulic column, substantially as set forth.

11. The combination of ports v^4 v^3 v^6 and

cavity v^5 of the valve, whereby the compressed air is exhausted, first from the air-conduit leading to the signal-actuating column, and next from the air-conduit leading to the switch-actuating column, substantially as set forth.

12. In combination with a hydraulic column and compressed-air conduit for effecting the forward stroke of a movement, a differential piston and cylinder continuously charged with a reversing pressure acting against the greater effective forward pressure communicated intermittently through the hydraulic column, substantially as set forth.

13. In combination with a close hydraulic column operative at one end on the larger piston-

area of a differential piston, two compressed-air conduits leading from a common main or reservoir, the one to the opposite end of the hydraulic column, and the other to the opposite end of the differential piston, whereby both switch-shifting motions shall be effected by the same motor at the same degree of pressure, substantially as set forth. 20

In testimony whereof I have hereunto set my hand.
